UNITED STATES PATENT OFFICE.

SAMUEL MORTENSON, OF CHICAGO, ILLINOIS, ASSIGNEE OF ONE-HALF TO JOHN B. MORTENSON, OF CHICAGO, ILLINOIS.

PACKAGE.

1,292,628.

Specification of Letters Patent. Patented Jan. 28, 1919.

Application filed January 21, 1918. Serial No. 212,877.

To all whom it may concern:

Be it known that I, SAMUEL MORTENSON, a citizen of the United States, and resident of Chicago, county of Cook, and State of Illinois, have invented certain new and useful Improvements in Packages, of which the following is a specification, and which are illustrated in the accompanying drawings, forming a part thereof.

10 The invention relates to improvements in packages and more particularly in packages for cigarettes and has for its object to provide a package of greater strength, ease in handling and general utility. To this end 15 the invention contemplates a construction in which the cigarettes or other articles are arranged in a sealed moisture proof package having a frictionally held lid adapted to tightly close the package after the moisture proof seal has been broken.

20 Further features of the invention will be described in connection with the construction shown in the accompanying drawings, in which;

25 Figure 1 is a perspective view of the completed package;

Fig. 2 is a perspective view of the package with the lid open, the several layers comprised in the side wall of the package being 30 each partly broken away;

Fig. 3 is a sectional view of a modified form of the package;

Fig. 4 is a perspective view partly broken away, showing the inner end of one of the 35 parts of the modified form of package illustrated in Fig. 3; and

Fig. 5 shows the several parts of the package illustrated in Figs. 1 and 2, separated from each other, each part being shown in 40 perspective from a central sectional plane.

In the form of construction illustrated in Figs. 1, 2 and 5, the package comprises an inner case 10, preferably of soft paper, paraffined or otherwise rendered moisture proof.

45 When this form of construction is used, the case 10 is formed by being folded about the contents of the package and hermetically sealed. Around the upper end of the case 10, but on the inside of the same, is placed 50 a cutting thread 9, if desired. When used, this thread is preferably held in position by paste or the like and one end, as 9^a, of the thread is passed between the folds at the adjacent end of the case and projects 55 upon the outside of the same. This arrange-

ment permits the entire folded upper end of the case to be cut out and completely removed by pulling upon the exposed end 9^a of the thread.

A container, generally designated 11, serves 60 either as an inclosure for the case 10 and its contents, as in Figs. 1, 2 and 5, or for directly receiving the contents of the package, as in Figs. 3 and 4. The body of the container 11 is preferably also formed 65 of soft moisture proof paper but is desirably of a heavier and more durable grade than that used for the case 10. The bottom of the container 11 is folded and hermetically sealed. The upper end of the container 11 70 comprises a stiff collar 12 of cardboard or the like and a friction lid 13, also of stiff material. The collar 12 is pasted within the upper end of the body portion of the container and preferably projects beyond 75 the same.

The lid 13 is most desirably formed with an interior marginal flange 22 adapted to make a close fit within the collar 12. Preferably, however, the entrance of the lid 80 flange 22 within the collar 12 is limited by providing the collar with a continuous in-standing shoulder 15 upon the inside. This shoulder is conveniently formed by securing a reinforcing strip 20 of cardboard or the 85 like around the inside of the collar adjacent its inner end. The reinforcing strip 20 serves both to stiffen the collar 12 and to so confine the contents of the package that it will not interfere with the entrance of 90 the lid flange 22 within the collar 12 even though the contents of the package may extend to substantially the level of the outer end of the collar.

When the inner case 10 is not used, a diaphragm 17, preferably of relatively thin moisture proof paper, is extended across the collar 12. As shown, this diaphragm is formed with a deep depending marginal flange 18 having a continuous intermediate 100 shoulder 24. When so formed, the diaphragm is secured in place by entering that part of the flange 18 which is beyond the shoulder 24 between the reinforcing strip 20 and the collar 12. The shoulder 24 of the 105 diaphragm flange thus overlies the shoulder 15 upon the inside of the collar 12, and space is provided for the entrance of the lid flange 22 between the collar and the inner part of the diaphragm flange 18. Further- 110

more, the body of the diaphragm extends over the contents of the package at the level of the outer end of the collar 12. If desired a cutting thread 19 is laid upon the shoulder 15 below the shoulder 24 of the diaphragm flange and extends entirely around the same with one end of the thread (not shown) projecting through the diaphragm. Upon removal of the lid 13 the projecting end of the thread 19 is exposed and pulling upon this end of the thread serves to cut out the entire diaphragm 17 immediately adjacent the shoulder 15 of the collar. The contents of the package are thus fully exposed in the same manner as with the construction illustrated in Figs. 1, 2 and 5. When the diaphragm 17 is used, the package is most conveniently filled from the bottom, before the lower end of the container 11 is closed, with the contents of the package extending to the body of the diaphragm. Up to the time the diaphragm is removed the package is hermetically sealed.

The package is given a finished appearance by covering the sides and bottom of the container 11 with a paper envelop 16 which may be decorated and printed in any desired manner. If the lid 13 and collar 12 are colored upon the outside to correspond with the decoration employed upon the envelop 16, a very attractive package is provided. The package is particularly intended for containing a quantity of articles, like cigarettes, which are removed one at a time and which must be protected until all are used. While the complete removal of the upper end of the inner case 10 or the diaphragm 17 renders all of the articles readily accessible merely by lifting the lid 13, replacement of the lid affords complete protection for the unused articles, particularly if the parts are suitably proportioned to insure a close fit of the flange 22 within the collar 12 and a firm seating of the flange 22 against the shoulder 15.

Preferably, the lid 13 is tied to the collar 12, as by a cord 14. If this cord is passed twice through the lid and collar to provide a pair of separate loose strands extending between the two, the lid will always be held in convenient position for its replacement, as in Fig. 2.

Usually a paper seal 23 will be pasted over the lid 13 and onto the sides of the package, as in Fig. 1. This seal will of course be broken when the lid is first removed. The improved package not only avoids the use of the more expensive grades of moisture proof wrapping materials, but the stiff collar and lid provide nearly the same protection against crushing as if the entire package were formed from stiff material. Furthermore, the unfolding and refolding of wrapping materials, each time a part of the contents is removed, is wholly

avoided and the protection against drying, afforded by the lid 13 even after the end of the case 10 or the diaphragm 17 has been completely cut away, is much greater than that afforded by a loosely folded wrapper and the inclosed articles are much more readily accessible. The cord 14 and seal 23 have been omitted from Fig. 3 to promote simplicity of illustration, but it will be understood that these may be employed with the form of construction illustrated in Fig. 3 in the same manner as with the form of construction illustrated in Figs. 1, 2 and 5. It will be understood that the package may be used for a variety of articles, the protection it affords against moisture and against crushing the contents, as also the accessibility of the contents, make it particularly desirable for confectionery, food products, drugs and the like.

I claim as my invention:

1. In a package, in combination, a sheet of soft and flexible moisture proof paper folded and pasted to constitute the closed side wall and bottom of a relatively deep casing, a stiff cardboard collar fitted to and having sealed connection with the upper end of the said casing, the said collar being formed with a continuous outwardly facing shoulder upon the inside of the same intermediate the ends of the collar, a moisture proof diaphragm extending across the collar, a cutting thread laid upon the shoulder of the collar and extending continuously around the same under the diaphragm, and a friction cover fitting within the collar over the diaphragm.

2. In a package, in combination, a sheet of soft and flexible moisture proof paper folded and pasted to constitute the closed side wall and bottom of a relatively deep casing, a stiff cardboard collar fitted to and having sealed connection with the upper end of the said casing, a cover frictionally entering the collar, a cardboard reinforcing strip of less width than the collar extending continuously around the collar upon the inside of the same adjacent its inner end, the outer edge of the strip constituting an outwardly facing shoulder limiting the entrance of the cover and a flanged moisture proof diaphragm fitting within the collar under the cover, the flange of the diaphragm being held between the collar and the said reinforcing strip.

3. In a package, in combination, a sheet of soft and flexible moisture proof paper folded and pasted to constitute the closed side wall and bottom of a relatively deep casing, a stiff cardboard collar fitted to and having sealed connection with the upper end of the said casing, a flanged cover frictionally entering the collar, a cardboard reinforcing strip of less width than the collar extending continuously around the collar upon the inside of the same adjacent its inner end and confining

the contents of the package within the cover flange, the outer edge of the strip constituting an outwardly facing shoulder limiting the entrance of the cover flange within the 5 collar, and a flanged moisture proof diaphragm fitting within the collar under the cover, the diaphragm flange being offset intermediate its ends continuously around the diaphragm and that part of the diaphragm 10 flange which is beyond the said offset being held between the collar and the said reinforcing strip.

4. In a package, in combination, a sheet of soft and flexible moisture-proof paper folded and pasted to constitute the closed side 15 wall and bottom of a relatively deep casing, a stiff cardboard collar fitted to and having sealed connection with the upper end of the said casing, a cardboard reinforcing strip 20 extending continuously around the collar upon the inside of the same adjacent its inner end but not extending to the outer edge of the collar, a flanged moisture-proof diaphragm fitting within the collar, the body 25 of the diaphragm conforming in size with the space inclosed by the said reinforcing strip but being located in the plane of the outer edge of the collar and the flange of the diaphragm extending to and having 30 sealed connection with the said reinforcing strip, and a cover having an instanding mar-

ginal flange frictionally entering the collar about the diaphragm flange, the outer edge of the said reinforcing strip constituting an outwardly facing shoulder limiting the entrance of the cover flange within the collar. 35

5. In a package, in combination, a sheet of soft and flexible moisture-proof paper folded and pasted to constitute a sealed wrapper 40 extending about the sides and over one end of a quantity of cigarettes or like articles, a stiff cardboard collar fitted to and having sealed connection with the said wrapper and encircling the said contents of the wrapper adjacent the other end of the same, a cardboard reinforcing strip extending continuously around the collar upon the inside of the same adjacent its inner end but not extending to the outer edge of the collar, a flanged moisture proof diaphragm fitting within the 45 collar and covering the last mentioned end of the said contents of the wrapper, the body of the diaphragm conforming in size with the space inclosed by the said reinforcing strip but being located in the plane of the 50 outer edge of the collar and the flange of the diaphragm extending to and having sealed connection with the said reinforcing strip, and a cover having an instanding marginal flange frictionally entering the collar about 55 the diaphragm flange. 60

SAMUEL MORTENSON.
